[57] CLAIM

The ornamental design for a power failure warning
light, as shown and described.

DESCRIPTION

FIG. 1 is a front perspective view of a power failure
warning light showing our new design;

FIG. 2 is a front elevational view thereof on an enlarged
scale;

FIG. 3 is a top plan view thereof on an enlarged scale;
FIG. 4 is a bottom plan view thereof on an enlarged
scale;

FIG. 5 is a left side elevational view thereof on an en-
larged scale;

FIG. 6 is a right side elevational view thereof on an
enlarged scale;

FIG. 7 is a rear elevational view thereof on an enlarged
scale;

FIG. 8 is a fragmentary cross-sectional view thereof
taken along line 8—8 of FIG. 2.
